[57] CLAIM

The ornamental design for a lower housing for an illuminated display stand, as shown and described.

DESCRIPTION

FIG. 1 is a top, front perspective view of a lower housing for an illuminated display stand showing my new design;

FIG. 2 is a top plan view thereof;

FIG. 3 is a bottom plan view thereof;

FIG. 4 is a front elevational view thereof;

FIG. 5 is a side elevational view thereof, the opposite side being a mirror image.

Fig. 1.

Fig. 2.

FIG. 3.

FIG. 4.

FIG. 5.
